UNITED STATES PATENT OFFICE.

WILLIAM A. COLE, OF DETROIT, MICHIGAN, ASSIGNOR OF ONE-HALF TO GEORGE J. MOBLEY, OF DETROIT, MICHIGAN.

DRIVING-BOX SHOE AND WEDGE.

Application filed August 16, 1926. Serial No. 129,305.

My invention relates to a new and useful improvement in a driving box shoe and wedge, adapted for use on locomotives and the like.

5. In the use of such shoes and wedges as now commonly manufactured, these parts are made from some cast metal which frequently fractures while in use, thus necessitating the removal and replacement of the 10 entire part while also lessening the safety of travel while being used in a fractured state.

It is an object of the present invention to provide a shoe and wedge of this class, in 15 the use of which fractures will be eliminated and in which the expense in retaining these parts in satisfactory operative condition will be reduced to a minimum.

It is another object of the invention to 20 provide a shoe and wedge of this class which will be most efficient in operation, rendering the movement of the journal box in the frame less resisted and making the riding of the vehicle smoother.

25. It is another object of the invention to provide a shoe and wedge of this class having a removable face made from comparatively soft material so that the wear on the journal box is reduced to a minimum, thus economizing in this regard, in that the journal boxes 30 may be used for a considerably longer length of time without replacement.

Other objects will appear hereinafter.

The invention consists in the combination 35 and arrangement of parts hereinafter described and claimed.

The invention will be best understood by a reference to the accompanying drawings which form a part of this specification and 40 in which,

Fig. 1 is a sectional view of a wedge embodying the invention showing it applied mounted in operative position.

Fig. 2 is a perspective view of a wedge 45 embodying the invention.

Fig. 3 is a plan view of the wear plate.

Fig. 4 is a plan view of the face of the wedge with the wear plate removed.

Fig. 5 is a sectional view taken on sub- 50 stantially line 5—5 of Fig. 2.

The invention is adapted for use on locomotives and similar vehicles in which a bolster frame 9 is provided with a downwardly projecting rib 10 having the vertically ex- 55 tending face 10' and the downwardly pro-

jecting rib 11 having the incline face 11'. Mounted between these ribs 10 and 11 is the journal box 12 which is adapted for vertical movement between the ribs when in use, this journal box serving as a journal for the axle 60 13, upon which the wheels 14 are mounted.

In the drawings I have illustrated in detail the invention applied to a wedge, but the invention is equally adapted for use on a shoe, the structure and operation of the 65 invention being substantially the same whether used on a wedge or used on a shoe.

The wedge comprises the main body 15 having an incline face adapted for engagement with the face 11' of the rib 11. Projecting outwardly from the sides of the body 70 15 are flanges 16 and 17 which embrace the rib 11'. Extending transversely of the wedge

are tapered dove-tailed grooves 18 and 19, the corners 18' and 19' being rounded so that the presence of sharp edges, which might chip off or break, are eliminated. This part of the wedge it is preferred to form from cast steel, so that a fracture of 80 the wedge when in use becomes practically impossible.

A wear plate 20, formed from a comparatively soft material, such as brass or the like, is provided on its outer face with the oil grooves 21 communicating with an opening 22, which projects through the 85 wear plate and through the rib 23, which projects outwardly from the face of the plate 20. A similar rib 24 projects outwardly from the same face of the plate 20 adjacent the opposite end, these ribs being tapered, as clearly appears in Fig. 3, and 90

adapted for engagement in the grooves 18 and 19, so that the wear plate 20 may be very easily mounted on the wedge by sliding the plate 20 transversely of the wedge, the 95 smaller ends of the ribs 24 and 23 first engaging in the larger ends of the grooves 18 and 19. When the wedge is mounted in position on the rib 11 the flange of the journal box 12 will embrace the opposite faces of 100

the wedge, so as to prevent removal of the wear plate from the wedge proper.

The structure is such that the wear plate may be very easily and quickly removed after it has been in use for some time on account of this method of attachment, so that in use under ordinary conditions it will become necessary but to replace the wear plate 20, the replacement of the wear plate 20 being a comparatively small cost to the 110

cost of replacing the entire wedge. Formed in the wedge 15 at opposite sides thereof are longitudinally extending openings 25 and 26 which communicate with a transversely extending opening 27 communicating with the passage 28, this passage 28 being in communication with the opening 22 when the wear plate is in operative position on the wedge.

The structure is such that when the device is in operative position, one of the passages 25 or 26 may be plugged and lubricant forced, by a grease gun or other suitable means, upwardly into the passage 26 and outwardly into the lubricant grooves 21, only proper lubrication of the wear plate may be very easily and quickly had at all times. By constructing the wedge in this manner, the wedge may be used for either right or left position, the innermost of the passages 25 and 26 being plugged so that the most accessible passage is available for injecting the lubricant as described. The presence of this lubricant will effect a reduction in the friction transmitted to the journal box because of its movements between the wedge and the shoe.

The shoe 29 illustrated in the drawings is constructed in a similar manner, this shoe 29 carrying the wear plate 20' provided with the ribs 23' and 24' which engage in the grooves. It is believed obvious that one skilled in the art will readily recognize the structure of the shoe from a description of the structure of the wedge and in the claims the reference to a wedge is intended to also embrace a shoe having the same structure.

In the drawings I have shown the wedge provided with an opening 32 registering with the opening 31 formed in the wear plate, these openings being usually openings formed in wedges of this class for the reception of the binding shoulders which serve to mount these wedges in operating positions on the ribs 11. With a wedge and shoe constructed in this manner the advantages sought for are attained and a most efficient device is provided.

While I have illustrated and described the preferred form of my invention, I do not wish to limit myself to the precise form of structure shown, but desire to avail myself of such variations and modifications as may come within the scope of the appended claims.

Having thus described my invention what I claim as new and desire to secure by Letters Patent is:

1. A wedge of the class described comprising: a main body having transversely extending grooves on one face; a wear plate; and ribs on said wear plate for engaging in said grooves and attaching said wear plate

to said main body, said wear plate being detachable from said main body upon said engagement except upon transverse relative movement of said main body and said wear plate.

2. A wedge of the class described comprising a main body having grooves formed on one of its faces, said grooves being tapered to provide a wider groove at one end than at the other; a wear plate; transversely extending tapered ribs on said wear plate for engaging snugly in said grooves for attaching said wear plate on said main body.

3. A wedge of the class described comprising, a main body having transversely extending grooves on one of its faces, said grooves being tapered to form one of the ends wider than the other; a wear plate of comparatively soft material; transversely extending tapered ribs on said wear plate, each adapted for engaging in one of said grooves for attaching said wear plate on said main body; the wear face of said wear plate having lubricant grooves formed therein and passages extending in said main body communicating with said grooves for affording a means of delivering lubricant to said grooves.

4. A wedge of the class described comprising, a main body having transversely extending grooves formed in one of its faces, said grooves being tapered to form one end wider than the other; a wear plate of comparatively soft material; transversely extending tapered ribs on one of the faces of said wear plate, each adapted for engaging in one of said grooves for attaching said wear plate on said main body; said wear plate having on its wearing face, lubricant grooves communicating through suitable passages with a longitudinally extending passage formed at each side of the lower end of said main body; each of said longitudinally extending passages affording a means for delivering lubricant to said grooves.

5. A wedge of the class described comprising: a main body; a detachable wear plate mounted on said main body, said plate and said main body having passages formed therein for affording a means of delivering lubricant through said passages to the wearing face of said wear plate, said body having transversely extending grooves formed in one face; and means on said wear plate engaging in said grooves for retaining the passages in said plate and said main body in registration with each other.

In testimony whereof I have signed the foregoing.

WILLIAM A. COLE.
